(Cl. D34—15)

To all whom it may concern:

Be it known that I, Edwin F. Silkman, a citizen of the United States, residing at Baltimore, in the State of Maryland, have invented a new, original, and ornamental Design for a Wooden Pull Toy, of which the following is a specification, reference being had to the accompanying drawings, forming part thereof.

I claim:

The ornamental design for a wooden pull toy,
as shown.

EDWIN F. SILKMAN.
